UNITED STATES PATENT OFFICE.

HARRY F. BOE, OF DAYTON, OHIO, ASSIGNOR TO THE VAILE-KIMES COMPANY, OF DAYTON, OHIO, A CORPORATION OF OHIO.

FLOAT SWITCH.

1,419,352.

Specification of Letters Patent. Patented June 13, 1922.

Application filed June 20, 1916. Serial No. 104,815.

To all whom it may concern:

Be it known that I, HARRY F. BOE, a citizen of the United States, residing at Dayton, in the county of Montgomery and State 5 of Ohio, have invented certain new and useful Improvements in Float Switches, of which the following is a specification, reference being had therein to the accompanying drawing.

10 This invention relates to a float switch. The object of the invention is to provide a float switch by which to control an electrically driven pump, the operation of which float is automatically controlled by the altitude or quantity of water in a storage tank. 15 It is a further object of the invention to render the connection between the float and the switch adjustable in order that the device can be adapted to different conditions, 20 and in order to vary the interval between successive operations of the switch.

In the accompanying drawings, I have illustrated one embodiment of my invention in which Fig. 1 shows the general system 25 with my invention applied thereto; Fig. 2 is a side elevation of the switch and the operating devices thereof with parts broken away and in section; and Fig. 3 is a plan view of the same.

30 In the embodiment of the invention herein shown I have utilized a storage tank 1 which may be situated in any suitable locality, such as the attic. At 2 I have indicated a suitable force pump with a suction pipe 3 communicating with a cistern or other source of fluid supply. A discharge pipe 4 is provided through which the fluid is discharged into the tank 1. At 5 I have shown a suitable relief valve. The tank 1 is also 35 provided with an overflow pipe, indicated at 6. The discharge pipe 4 is connected to a cold water pipe 7 leading to the fixtures. A hot water pipe is indicated at 8. To operate the pump I use a suitable electric motor 9, 40 conductors 10 and a main controlling switch 11. The conductors 10 are also operatively connected to a quick-acting switch 12 which in the embodiment of the invention here shown is situated upon the storage tank 1. 45 This switch is automatically operated and for this purpose I have provided a float 13 within the tank. The main features of the switch here shown are described and illustrated in United States Letters Patent No. 50 1,195,232, granted August 22, 1916, to Hugh

W. Kimes. The switch comprises a suitable support 14 which is connected to the tank, a fixed contact member 15 and a movable contact member 16. The movable contact member is actuated by a suitable actuating device which, in the present instance, comprises a lever 17 pivoted at 18 to a suitable part of the frame. Pivoted at 19 to the lever 17 is a spring-actuated part 20 having converging surfaces forming a nose 21. This part 60 is normally held in projecting position by a spring 22 which is pocketed in a suitable socket 23 upon the lever 17. A controlling lever 24 is also provided and this lever is pivoted at one end upon an axis pin 25. The 65 opposite end of the lever has a roller 26 in engagement with the nose 21. There is provided a pair of spaced-apart stops 28 and 29, which are preferably rigidly supported by the frame 14, and located in the path of 70 the levers 17 and 24, the lever 17 having a suitable projection 30 adapted to engage either one stop or the other according to its position. To hold the lever 17 in yieldable engagement with the end of the lever 24 I 75 have utilized a spring 31 attached at one end to the fixed frame-work, as at 32, and having its opposite end attached to the lever 17 at 19. The spring 22 is stronger than the spring 31 and overcomes the action of the 80 latter when the switch is held open. For actuating the controlling lever 24 to open and close the switch I have provided a pair of relatively adjustable disks 33 and 34. These disks are rotatably mounted upon the 85 axis 25 and rotate independently of the lever 24. The adjacent faces of the disks are serrated, as shown at 35, and are held in adjusted positions relatively to each other by a lock nut 36. The disk 33 has a cut away portion 37 and the disk 34 is provided with a similar cut away portion 38, thereby forming 90 spaced-apart shoulders or abutments 39 and 40 and 41 and 42 upon the disks 33 and 34, respectively. These abutments are arranged 95 on opposite sides of a shoulder or abutment 43 upon the lever 24.

In the position shown in Fig. 2 the abutment 41 is in engagement with the abutment 43, which is the position occupied by said parts when the water in the tank has fallen to a predetermined level, the switch being closed, and the motor 9 being caused to operate the pump for supplying water to the tank. As the water within the tank rises 100 110

the disk will begin to move counterclockwise until the abutment 40 engages the upper side of the lever 24, moving it downwardly, depressing the part 20, and moving the roller 26 to the opposite side of the nose 21 from that shown in Fig. 2. It will be seen that the relative distance between the abutments can be adjusted so that the interval between the making and breaking of the circuit can be varied. One of the disks is provided with a rigid arm 44 and this arm in turn is adjustably connected, as at 45, to a rod 46 to which the float 13 is fixed.

From the above description of the mechanism it is thought that the operation will be obvious. It will be seen that the float can be adjusted by means of the double adjustment described so that when the fluid within the tank rises to a proper level the operation of the pump will be stopped through the breaking of the circuit and then as the fluid lowers to a certain level the operation will again commence through the closing of the circuit. To insure this the parts can be delicately adjusted.

While I have shown and described one embodiment of my invention it will be understood that the same has been chosen for the purposes of illustration only and that I do not desire to be limited to the details of construction shown and described, for obvious modifications will occur to a person skilled in the art.

Having thus fully described my invention, what I claim as new and desire to secure by Letters Patent, is:—

1. In a device of the character described, a quick acting switch, a lever for actuating said switch, a device controlled by the rise and fall of fluid and provided with spaced members rotarily mounted upon a common axis and having oppositely facing shoulders to alternately engage said lever to move the same back and forth, said members being relatively adjustable.

2. In a device of the character described, a switch, a pivoted lever for controlling said switch, a two-part disk shaped member rotatably mounted on the axis of said lever and provided with relatively adjustable portions on opposite sides of said lever adapted to engage the same to alternately move it back and forth.

3. In a device of the character described, a switch, a pivoted lever for controlling said switch, a pair of relatively adjustable devices mounted on a common axis, and comprising portions forming shoulders adjustable one towards the other and located upon opposite sides of said lever.

4. In a device of the character described, a switch, a pivoted controlling lever for said switch, a pair of relatively adjustable members provided with shoulders, rotatably

mounted upon the axis of said lever and embracing opposite sides thereof, and means for actuating the same to move the lever first in one direction and then in the other.

5. In a device of the character described, a switch, a controlling device therefor and means for actuating said controlling device first in one direction and then in the other, said means comprising a pair of members mounted on a common axis, and having shoulders in engagement with said controlling device, said shoulders being adjustable one towards the other.

6. In a device of the character described, a switch, a pivoted lever controlling said switch, a device rotatably mounted on the axis of said lever and provided with shoulders adapted to engage opposite sides of said lever to move the same back and forth, and a float adjustably connected to said device.

7. In a device of the character described, a switch, a controlling device for said switch, and a float connected to said controlling device, the connection between said switch and float comprising frictionally engaged disks having oppositely facing shoulders to be engaged by said device, said disks being rotarily adjustable whereby the height of the float and the interval between successive operations of the switch can be adjusted.

8. In a device of the character described, a switch, a pivoted lever controlling said switch and having a projection thereon, rotatable disks mounted on the axis of said lever and provided with oppositely facing shoulders adapted to engage said projection, means for adjusting the position of said shoulders, and a float connected with one of said disks.

9. In a device of the character described, a switch, a controlling device for said switch arranged to actuate the movable member of the switch to cause quick action of the latter, and a float connected with said controlling device through rotarily adjustable members which are movable with the float and are constructed to engage said device at predetermined points in the travel of the float, whereby the controlling device is operated when the float reaches predetermined upper and lower limits of its travel.

10. In a device of the character described, a switch, a pivoted controlling device for said switch, a float, and means comprising rotatably adjustable disks having oppositely facing shoulders, said disks being located between said float and device for determining, adjustably, the upper and lower positions occupied by the float when the controlling lever will be actuated to open and close the switch.

In testimony whereof, I affix my signature.
HARRY F. BOE.
